IGNITION TIMER AND METHOD OF
CONTACT POINT ADJUSTMENT

Lucius D. Watkins, Milwaukee, Wis., assignor to
Outboard, Marine & Manufacturing Company,
Waukegan, Ill., a corporation of Delaware

Application March 15, 1951, Serial No. 215,817

17 Claims. (Cl. 200—31)

1

This invention relates to an ignition timer and method of contact point adjustment.

It is the object of the invention to facilitate breaker point and timing adjustment by releasably mounting the entire breaker assembly for bodily adjustment. Desirably the assembly is subject to the action of a spring which is not sufficiently strong to open the contacts against the bias of the breaker spring, and which urges the entire assembly toward the breaker cam so that, given a proper rotative datum position of the cam, the assembly will automatically engage the cam follower with the cam in a position which necessarily represents a properly timed setting, and in which said assembly can thereafter be fixed.

The invention further contemplates a means for indicating or establishing the proper datum position for the cam by means of a detent normally out of engagement with a cam-connected rotor, but movable to a position for such engagement in the same operation which releases the breaker assembly for free movement in response to the aforesaid spring.

From a method standpoint, the invention is characterized by the fact that adjustment is made by the bodily movement of the breaker mechanism with the points closed, such adjustment being made in a direction having a substantial component radially of the cam, to bring the cam follower into engagement with a predetermined portion of the cam intermediate its positions of minimum and maximum cam displacement, and thereupon clamping the breaker mechanism against further movement having a component radially of the cam, so that displacement of the cam follower from the selected point on the cam to the peak thereof will necessarily represent a given opening of the points.

For convenience of illustration, the invention is shown in conjunction with the fly wheel magneto and timer plate of a two-cycle engine, but the invention is by no means limited to this application.

In the drawings:

Fig. 1 is a plan view of an engine fly wheel with portions broken away to expose the breaker assembly and cam.

Fig. 2 is a view in side elevation of the engine crank shaft bearings and fly wheel, portions broken away to the plane indicated at 2—2 in Fig. 1.

Fig. 3 is a fragmentary detail view on the section similar to that of Fig. 2 showing the breaker assembly carriage released for self-ad-

2

justment and the detent raised to interact with the fly wheel.

Fig. 4 is an inverted plan view fragmentarily illustrating the spring detent in engagement with the fly wheel.

Fig. 5 is a view fragmentarily illustrating a modified embodiment of the invention on a section similar to that of Fig. 2.

A portion of an engine crank case is illustrated at 6 in Fig. 2. From it projects a bearing sleeve 7 within which a bushing 8 rotatably supports crank shaft 9. In this type of engine, the crank shaft also serves as a cam shaft (having the cam 10 mounted thereon). Rotation is clockwise as viewed in Fig. 1.

Rotatable upon the outside of the bearing sleeve 7 is the usual timer plate 11, the collar or hub 12 of which is rotatably fitted to bearing sleeve 7. For timing purposes, the plate 11 is usually adjustable angularly, a fragment of the handle 13 being shown to exemplify this feature. For the purposes of the present invention, the plate 11 may be regarded as fixed.

At its upper end, the shaft 9 carries the rotor 14 which, in this device, comprises a fly wheel magneto. For starting purposes, a starting pulley 15 is carried on the top of the fly wheel. Interiorly of the rim 16 of the rotor or fly wheel 14 is a magnet 17 which, however, forms no part of the present invention. At one point, the rim 16 of the fly wheel 14 has a shoulder which is here provided by a marginal notch 18, for purposes hereinafter to be described.

The entire breaker mechanism is mounted on a carriage 20 which is capable of free movement on the timer plate 11 to and from the axis of cam shaft 9. For the purposes of the present disclosure, the carriage 20 comprises a plate pivoted on a stud 21 which projects upwardly from timer plate 11 and about which the plate 20 oscillates freely except when clamped to the plate. In order that it may be clamped to the plate during normal operation, there is a clamping bolt 22 screw-threaded through the timer plate 11, as shown in Fig. 2, and passing through a slot 23 in the carriage 20, such slot being generally arcuate about the center of oscillation on stud 21. The nut 24 adjustably fixed to bolt 22 engages the clamping washer 25 when the screw is turned downwardly in timer plate 11 to clamp the carriage 20 to the timer plate. By screwing the bolt 22 upwardly, as viewed in Fig. 2, the clamping pressure may be released sufficiently to permit the carriage to oscillate freely upon its pivot stud 21, subject to the bias of the

torsion spring 26 which is coiled about the stud and has its end 27 engaged with anchorage 28 and its free end 29 engaged with a margin of carriage 20.

The fixed contact point 30 is mounted rigidly on the carriage and provided with wire terminal 31, the point and terminal being insulated at 32 from the carriage. The movable contact point 33 is carried by spring 34 from a spring anchorage 35 fixed to the carriage. The points may be separated by the cam 10 when the nose of the cam registers with a cam follower 36 engaged with spring 34, whereby the spring 34 is flexed to disengage contact point 33 from engagement with contact point 30. In the present device, the cam follower 36 comprises a push rod reciprocable in the bearings 37, 38 provided by the carriage. It is, however, broadly immaterial how motion is transmitted through the cam follower to the movable contact point, since it will be obvious that a variety of mechanical arrangements can be used to obtain the advantages of the present invention, so long as the breaker mechanism is mounted on a carriage for bodily movement to and from the cam. The relative strength of the springs 23 and 34 should be such, however, in relation to the structure used, that the spring 26 will not exert sufficient thrust or torque upon the carriage 20 so that the reaction of the pressure of cam follower 36 upon cam 10 will open the points. Bearing in mind that the relative strength of these two springs may be varied according to the mechanisms used to transmit cam motion to the moving point, this relationship may be described generically by saying that the effective strength of spring 34 to resist the opening of the contacts is greater than the effective strength of spring 26 exerted in a direction to effect such opening.

In the ordinary breaker mechanism, fixedly mounted on a timer plate or equivalent, the proper setting of the points involves first, the adjustment of the cam nose into registry with the cam follower, so that the latter is moved to the position which it occupies when the points are most widely separated. One of the points, usually the relatively fixed point, is mounted on a screw which is then adjusted to a specified spacing from the open movable point, such spacing being determined by a thickness gage, and requiring a substantial amount of technical skill for its proper achievement. Moreover, the adjustment of points must either be made through a hole in the fly wheel, or the fly wheel has to be removed to give access to the parts requiring adjustment. This operation is performed at the time the parts are initially assembled and the same operation must be repeated each time the points are trued, or each time sufficient wear occurs to affect proper timing.

The present invention eliminates completely all need for technical skill, and for the use of any gage. The cam is first positioned to a predetermined ignition position or breaker point opening position. Even this establishment of the relative positions of the parts is desirably accomplished automatically through the use of a detent 40 confined between flanges 41, 42 on the under surface of the timer plate 11 and having its free end pivotally movable into engagement with the shoulder provided by the notch 18 on the lower margin of the rim 16 of the fly wheel 14. The detent is normally held disengaged from the fly wheel by the compression spring 43, as shown in Fig. 2. This spring urges the detent down-

wardly against the washer 44 on the screw 22. When the screw 22 is turned upwardly in a direction to unclamp the carriage 20 for oscillatory movement under the torque of spring 26, the same upward releasing movement of the screw which unclamps the carriage carries the detent 40 up into a position where, as the fly wheel is rotated, the detent will engage in notch 18. Accordingly, when the operator releases the carriage, all he has to do is to rotate the fly wheel until the detent engages in the notch, whereupon the cam nose 10 will automatically be in the precise position required for proper timing.

Meantime, the carriage 20 will have been oscillated by spring 26 to a position such that cam follower 36 engages the side of the cam. With the cam in the position determined by the detent 40, the relationship between the cam follower and the cam will automatically be such as to achieve exactly the displacement of the contact point 33 which is required for properly timed breaker operation. This is true for the reason that the effective strength of spring 34 is greater than the effective strength of spring 26. Thus, no matter how long or how short may be the contact points 30 and 33, the spring 34 will hold them together at the time the cam follower 36 is engaged with the side of the cam so that the separation ultimately effected by the cam will be exactly that degree of separation required for proper operation.

Consequently, all that the operator now has to do is to re-clamp the carriage 20 to the timer plate in the position to which the carriage has adjusted itself. Screwing the screw 22 downwardly in the timer plate simultaneously clamps the carriage in adjusted position and retracts the detent 40 out of the path of the fly wheel, leaving the parts free for operation conventionally.

To achieve this result, the operator has been required only to loosen the screw 22, rotate the fly wheel until the detent 40 engages and thereupon tighten the screw 22.

In the construction shown in Fig. 5, a prying action has been substituted for a screwing action as a means of releasing the carriage and operating the detent. The timer plate is here designated as 110. It has a depending lug at 45 with a notch 47 in which the free of the detent 400 is pivoted. The bolt 220 is freely reciprocable through the slot 23 of carriage 20 and through a hole 48 in the timer disk 110. Its head 49 clampingly engages the carriage while a nut 50 on its lower end supports the detent 400 against the compression of the spring 43. By simply inserting a screwdriver or other lever 51 beneath bolt 220, and fulcruming the point of the screwdriver upon the shoulder 52 of boss 46, it is possible to lift the bolt to engage the detent 400 in the notch 18 of the fly wheel rim, while simultaneously freeing the carriage 20 for self-adjustment as above described. In this device, as in that shown in Figs. 1 to 4, the operator has only to unclamp the carriage, rotate the fly wheel to the appropriate cam position, and re-clamp the carriage. In both devices shown, an additional feature consists in the automatic determination of the correct cam position by means of a detent which becomes effective to engage a shoulder on the fly wheel rim coincidentally with the unclamping of the carriage and is retracted to an inoperative position when the carriage is again clamped to the timer plate.

Assuming that the timer plate is relatively os-

cillatable, as in the exemplification shown, its oscillation will serve to advance or retard the spark in the usual manner without in any way affecting the setting of the points as automatically self-determined by the movement of the carriage to engage the cam follower with a selected portion of the cam at a time when the points are closed.

I claim:

1. In an ignition timer comprising a cam and a breaker mechanism including a cam follower and relatively fixed and movable contact points, the latter being connected to be actuated by the cam follower away from the fixed point, the improvement which comprises a carriage upon which said breaker mechanism is mounted for bodily movement in a direction which includes a substantial component of cam follower movement radially of the cam, means guiding the carriage for such movement, a spring biasing the carriage for movement of the cam follower toward the cam, and a spring biasing the movable contact point toward the fixed contact point, and the effect of which to prevent separation of said points is greater than the effect of said first mentioned spring in a point separating direction, whereby the movement of the carriage effected by the first mentioned spring will advance the cam follower into contact with the cam, without separating said points, and means for releasably clamping the carriage in the position in which it is thus advanced, as determined by engagement of the cam follower with the cam.

2. In an ignition timer which includes a cam, a timer plate oscillatable coaxially with the cam, and breaker mechanism having a cam follower, a movable contact point connected to be actuated by the cam follower, a fixed point from which said movable point is separated when actuated by the cam follower, and a contact spring biasing the movable contact point toward the fixed contact point aforesaid; the improvement which comprises a carriage upon which said spring and points and cam follower are unitarily mounted, means guiding said carriage for movement in a direction having a substantial component in which said cam follower is advanced toward said cam, a spring biasing said carriage for the advance of the cam follower toward the cam and less effective through said cam follower to separate said points than is the first mentioned spring to bias the movable point into engagement with the fixed point, and means for securing the carriage to the timer plate in the position to which it is adjusted by the last mentioned spring, the carriage and cam follower and the said points and the spring first mentioned being unitarily oscillatable with the timer plate coaxially with the cam when the carriage is thus secured to said plate.

3. The device of claim 2 in further combination with means for establishing a predetermined angular adjustment of the cam respecting said plate.

4. The device of claim 3 in which said establishing means comprises physically engageable parts respectively connected with the cam and said plate for determining positively the desired angular position of the cam relative to the plate.

5. The device of claim 4 in which one of said parts comprises a fly wheel provided with a shoulder and the other of said parts comprises a detent movably mounted on the plate to be advanced and retracted from the path of said fly wheel shoulder and connected with said carriage

securing means to be advanced in the release of said carriage securing means and retracted in the movement of said means which secures the carriage to the plate.

5. 6. In an ignition timer comprising a cam, a cam follower and relatively fixed and movable contact points, the latter being provided with a spring biasing it toward the former and being operated by said follower in a direction to displace it from contact with the fixed point against the bias of said spring, the improvement which comprises the combination of a carriage upon which the fixed point is mounted and having means supporting the follower and spring and movable point, a support for the carriage, a pintle connected with the support and upon which the carriage is pivoted for oscillatory movement, the said cam follower being supported on the carriage for engagement with said cam on a radius of the cam which is remote from a radius of said cam drawn to said pintle, whereby the said cam follower will move to and from the cam in the course of carriage oscillation upon said pintle, a spring connected between the support and the carriage to bias the carriage in a direction of oscillation which advances the cam follower toward the cam, the effect of said spring upon the movable contact point where the cam follower engages the cam being less effective to open said point than is the first mentioned spring to bias the movable contact point into engagement with the fixed contact point, and means for clamping the carriage to said support in the position to which the carriage is adjusted by the spring first mentioned and determined by the closed position of the movable contact point.

7. The device of claim 6 in which said clamping means include a bolt extending through the support and carriage and axially movable to and from carriage clamping position.

8. The device of claim 7 in further combination with cam setting means which comprises a rotatable part connected with the cam and provided with a shoulder and a detent mounted on said support and having means interlocking it therewith against angular displacement with said part, said detent being movable to and from the path of rotation of said shoulder and being connected with said bolt for advance to said path when said bolt moves axially for the release of the carriage and for movement from said path when said bolt moves axially for the clamping of said carriage.

9. The device of claim 8 in which said detent is provided with a third spring seated against said support and biasing it toward its retracted position.

10. The device of claim 9 in which said bolt is screwthreaded to said support and operated axially by rotating it upon its threads.

11. The device of claim 9 in which said bolt is freely reciprocable to said support and carriage and biased to clamping position by the spring of said detent.

12. The device of claim 9 in which said support comprises a timer plate oscillatable substantially co-axially with said cam.

13. The device of claim 12 in which the shoulder part connected with said cam comprises a fly wheel.

14. A timer comprising in combination a shaft provided with a cam, a timer plate angularly adjustable substantially coaxially with the shaft, a fly wheel connected with the shaft and having a depending margin encircling said plate and pro-

vided with a shoulder determinative of a selected cam position when engaged by an appropriate detent, a detent mounted on the timer plate for movement to and from the path of said shoulder, a clamping bolt axially movable through the timer plate and connected with said detent to control the position thereof, a carriage mounted on the timer plate and having a slot through which said bolt passes, the said bolt being adapted in one position of axial adjustment to clamp the carriage to the plate, breaker mechanism mounted in its entirety upon the carriage and comprising relatively fixed and movable points, a spring supporting the movable contact point and biasing it toward the fixed contact point, and a cam follower cooperating with the cam and arranged to transmit motion from the cam to the movable contact point to effect separation thereof from the fixed contact point against the bias of said spring, the said carriage being provided with means mounting the fixed contact point, the spring, and the cam follower, and a pintle connected with the timer plate and upon which the carriage is mounted for oscillation, the said pintle being disposed on a projected radius of said cam remote from the radius of said cam upon which said cam follower engages said cam, whereby the oscillatory movement of the carriage upon the pintle will advance and retract the cam follower from the cam, and a spring lightly biasing the carriage in a direction to advance the cam follower to the cam, the carriage being free for movement in said direction when released from clamping engagement by said bolt, and the spring last mentioned being less effective through said cam follower upon the movable contact point in a direction to open said point than is the spring first mentioned in its bias of said movable con-

tact point toward closed position respecting the fixed contact point.

15. In an ignition timer mounted for coaction with a cam having a path of movement, the combination with a carriage having releasable means for fixing its position respecting the path of the cam and having a fixed and movable contact, a contact spring biasing said movable contact toward said fixed contact and a cam follower actuated by said cam to oppose said contact spring, of a mounting on which the carriage is pivotal toward and away from the path of said cam, a carriage spring biasing said carriage toward said cam against the bias of said contact spring, said springs being of different strength with the contact spring sufficiently stronger than the carriage spring to insure closure of said contacts when both are permitted to freely react against said cam follower.
20. The device of claim 15 in further combination with means for establishing a predetermined angular adjustment of the cam respecting the carriage, said means comprising parts connected to said cam and carriage which releasably interlock in said predetermined angular adjusted position.
25. 17. The device of claim 16 wherein said releasable means for fixing the position of the carriage respecting the path of the cam further comprises means to releasably interlock said parts on release of said carriage.
